UNITED STATES PATENT OFFICE

2,398,622

REVERBERATORY FURNACE

Tony Crneich, Noranda, Quebec, Canada, assignor
to M. H. Detrick Company, a corporation of
Delaware

Application August 24, 1942, Serial No. 456,110
In Canada September 24, 1942

2 Claims. (Cl. 263—46)

This invention relates to furnace construction, and to refractory sections or blocks for use in furnace construction, and more particularly to members in the side wall construction of reverberatory furnaces.

In such a furnace, the charge employed, which consists of hot roasted calcines, is fed downwardly through fettling pipes spaced longitudinally along each side of the furnace at one end thereof, and tends to build up and substantially cover the side walls. The charge is progressively fed into the furnace and melted by powdered coal burners, and the melted charge then flows to the opposite end of the furnace from the burners, where the molten slag and matte are tapped off. The upper portion of the side walls of the furnace are frequently exposed, particularly between the charging holes, and are thus exposed to an extremely high temperature which ranges in the neighborhood of 2700° F.

In prior art constructions, silica brick is ordinarily employed for the top portions of the side walls, which results in the side walls being rapidly burned out when not covered by the furnace charge.

A principal object of the present invention is the provision of a relatively large refractory section or block which is adapted to be employed in building up or repairing the upper portion of the side walls of a reverberatory furnace.

Another important object of the invention is the provision of such a refractory section which is suspended from and supported by the frame members normally employed for supporting the roof of the furnace.

A further important object of the invention is the provision of a refractory section or block which comprises a block of basic magnesite material, to which has been added a suitable binder, and which is supported by projections extending from the block, preferably by a bent wire embedded in the magnesite filler. In such construction a reinforcing plate is preferably employed in the central portion of the block.

Another important object of the invention is to greatly reduce the operating cost of a reverberatory furnace and materially to increase the facility of repairing the same by providing large, suspended, refractory sections or blocks from the upper portion of the side walls of the furnace.

Numerous other objects and advantages of the invention will be apparent as it is better understood from the following description, which, when taken in connection with the accompanying drawing, discloses a preferred embodiment of the invention.

In the drawing,

Figure 1 is a transverse, vertical sectional view, with parts broken away, through a portion of a reverberatory furnace, and showing the use of the present invention;

Fig. 2 is a vertical, longitudinal section taken substantially on line 2—2 of Figure 1;

Fig. 3 is a top plan view of the improved refractory section or block of the present invention;

Fig. 4 is a front view of the improved refractory section or block of the present invention; and

Fig. 5 is a side view of the improved refractory section or block of the present invention.

Referring more particularly to the drawing, part of a reverberatory furnace is disclosed therein which comprises a plurality of vertical supporting members or backstays 11 which are arranged in longitudinally spaced relationship to each other in two rows. Extending across and supported by the opposed backstays 11 are a plurality of longitudinally spaced, horizontally disposed supporting members or beams 12. Supported by the beams 12 and extending transversely thereof and longitudinally of the furnace are a plurality of arch suspension beams 13, from which tile or brick supports 14 are suspended by suitable suspension rods 15. Each of the brick supports 14 carries a plurality of refractory bricks 16 to form a suspended roof structure for the furnace. This roof structure is substantially identical to that disclosed in Canadian Patent No. 381,931, issued June 6, 1939, to Charles F. Pollen.

30 A charge floor 17 is disposed above the furnace roof in well-known manner, and is provided with suitable openings adjacent and spaced inwardly from each of the rows of backstays 11, within which are disposed calcine bins 18. A calcine car 19 of usual construction is mounted for longitudinal movement above each of the bins 18. A plurality of fettling pipes 21 extend downwardly in longitudinally spaced relationship from each calcine bin 18 to a point slightly below the refractory bricks 16 of the suspended roof structure of the furnace, and the usual fettling operator's platform 22 is provided along the outer side of each row of backstays 11. The side walls of the reverberatory furnace are supported by the backstays 11 and normally comprise silica bricks 23 which are laid in the usual manner, although being shown in Figs. 1 and 2 as solid wall structures.

45 In the operation of such a reverberatory furnace, the charge employed consists of hot roasted calcines which are fed from the cars 19 to the bins 18, and through the fettling pipes 21 into the interior of the furnace. The charge is progressively fed into the furnace, and tends to build up and substantially cover the side walls 23, as shown at 24 in Fig. 1. The charge 24 is melted by powdered coal burners (not shown), and the melted charge flows to the end of the furnace opposite that at which the burners and fettling pipes 21 are disposed, where the molten slag and matte are tapped from the furnace.

The upper portions of the side walls 23 are frequently exposed, particularly between the longitudinally spaced fettling pipes 21, and are thus subject to an extremely high temperature, since the temperature of the furnace normally ranges in the neighborhood of 2700° F. In the prior art constructions, silica brick is ordinarily employed for these upper portions of the side walls.

The present invention contemplates the provision of a number of relatively large refractory sections or blocks, indicated generally by the reference numeral 25, as the upper portions of the side walls 23 of the furnace. In actual practice, each refractory section or block is preferably approximately 36" in height, 15" wide and 9" thick. These sections are disposed directly above the refractory bricks 23 and extend to a point adjacent the lower surfaces of the outer roof refractories 16.

As will best be seen from Figures 2 to 5, each refractory section 25 comprises a block of non-acidic or basic refractory material 27, preferably magnesite (magnesia), which is mixed with any suitable binder. If desired, chrome can be used with magnesite as the plastic basic material. A metal supporting member or wire 28 is embedded in the basic refractory material, and the wire preferably has the shape indicated in Figures 2 and 4, with outwardly curved end portions disposed adjacent the bottom of the block 25 and an upper looped or bent-back portion extending above the upper edges of the block. The wire 28 comprises the means by which the refractory section or block 25 is suspended and held in proper position.

The block 25 is preferably provided with a reinforcing plate 29. This reinforcing plate or metal sheet 29 extends centrally of the thickness of the block and preferably extends throughout the height and width of the block.

Suspension rods 30, which are substantially similar to the suspension rods 15, are suspended from the outer beams 13, as shown in Figure 1, and are provided at their lower ends with hook shaped portions for engaging the wires 28 of the refractory sections or blocks 25. In this manner, the refractory sections or blocks 25 are suspended in side by side relationship (Figure 2) directly above the silica brick 23 to form the upper portion of the side walls of the furnace. Suitable refractory bricks 31 (Figures 1 and 2) may be laid upon the suspended sections 25 to provide outward extensions of the suspended roof structure.

With the above described construction, the upper portions of the side walls of the refractory furnace will withstand the extremely high heat to which they are exposed for a much longer period of time than is normally the case when the silica bricks 23 are employed for such portions of the walls. The magnesite, or magnesite and chrome, material of which the blocks are made, will withstand a high temperature for a much greater length of time than the silica brick 23. A very appreciable saving in operating cost of the furnace is thus effected, since repair or replacement of the upper portions of the side walls will be greatly reduced. The present construction has the further advantage of facilitating any repair or replacement of the upper portions of the side walls of the furnace which may become necessary after a period of long usage. This is due to the fact that the suspending of the refractory sections or blocks 25 greatly simplifies the installation thereof in comparison

with the usual procedure of laying the silica brick 23.

The refractory sections 25 also have the material advantage of use as repair units in reverberatory furnaces in which they have not been originally installed. In such a construction, if a piece of one of the side walls burns out, it is necessary merely to clear a hole of sufficient size to receive one or more of the refractory sections 25 and position the latter therein. In this regard, as well as in an initial installation, the relatively large size of the refractory sections or blocks 25 is of primary importance.

The production of the refractory sections or blocks 25 without an outside metal covering or container is also of importance in that it avoids the use and expense of such metal containers, which metal is of course burned away during the operation of the furnace.

The improved refractory sections or blocks 25 of the present invention can be formed in molds, and the refractory material such as magnesite can be either hand tamped or can be tightly packed together with an air hammer, after suitably positioning therein the suspension wire 28, and the reinforcing plate 29 where such plate is employed.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a reverberatory furnace provided with supports, a plurality of refractory blocks suspended from said supports to form a roof structure, and side walls comprising lower fixed portions of refractory brick and upper portions forming a continuation of said lower portions and extending therefrom to said roof structure, said upper portions being constituted by a plurality of relatively large refractory sections suspended from said supports, each of said sections comprising a block of non-acidic refractory material and a suitable binder therefor, a metal reinforcing plate embedded in said block and extending substantially from top to bottom thereof in parallel relation to the heat receiving face of the block, and a supporting member embedded in and extending from said refractory block to provide means for suspending said refractory section.

2. In a reverberatory furnace provided with supports, a plurality of refractory blocks suspended from said supports to form a roof structure, and side walls comprising lower fixed portions of refractory brick and upper portions forming a continuation of said lower portions and extending therefrom to said roof structure, said upper portions being constituted by a plurality of relatively large refractory sections suspended from said supports, each of said sections comprising a block of non-acidic refractory material and a suitable binder therefor, a reinforcing plate positioned in said block and extending substantially throughout the height and width of said block, and a supporting member embedded in and extending from said refractory block to provide means for suspending said refractory section.
